UNITED STATES PATENT OFFICE.

THOMAS J. HAYES, OF ROSLINDALE, MASSACHUSETTS, ASSIGNOR TO ARBETTER FELLING MACHINE COMPANY, OF BOSTON, MASSACHUSETTS, A CORPORATION OF MAINE.

PRESSER-FOOT FOR BLINDSTITCH SEWING-MACHINES.

1,397,516.

Specification of Letters Patent.

Patented Nov. 22, 1921.

Application filed August 20, 1917. Serial No. 187,059.

To all whom it may concern:

Be it known that I, THOMAS J. HAYES, a citizen of the United States, and resident of Roslindale, county of Suffolk, State of Massachusetts, have invented an Improvement in Presser-Feet for Blindstitch Sewing-Machines, of which the following description, in connection with the accompanying drawing, is a specification, like characters on the drawing representing like parts.

This invention relates to improvements in presser foot mechanisms for blind stitch sewing machines, particularly of the type in which the stitches are formed by a curved 15 oscillating needle and complementary stitch forming mechanism located above the work support.

The principal object of the invention is to provide an improved guiding means for 20 the superimposed layer which will permit the machine to operate properly in stitching superimposed layers of widely different thicknesses to the main layer of material and to provide a guiding means which may readily be removed from operative position in 25 order to permit thick seams to pass through the presser foot to the stitch forming mechanism and also to enable the operator to see to manipulate the work as in turning the 30 corners of garments, etc.

The present invention comprises certain improvements upon the structure shown in my prior application No. 94987 filed May 2, 1916, which discloses a presser foot having 35 a needle throat, and a guide located adjacent said needle throat having means for engaging the upper surface and edge of the superimposed layer and operating to direct said superimposed layer in advance of and adjacent to the stitching point which is located 40 within the needle throat.

More specifically the present invention is an improvement upon the structure disclosed 45 in my prior application No. 151,427 filed Feb. 28, 1917 which discloses a guide for the superimposed layer of the character above described which is so mounted as to be removable from guiding position in order to permit thick seams to pass through the 50 stitching mechanism and to enable the operator to observe the work at the stitching point which is particularly desirable in turning corners, etc.

In the use of blind stitch sewing machines 55 for making garments of different kinds and

for different seasons a wide variety of material is operated upon and as blind stitch sewing machines are mainly used for felling lining to the main body of material the thickness and quality of the lining varies greatly.

The principal objects of the present invention are to provide guiding means which will operate properly to present the superimposed layer, or lining, to the stitch forming mechanism when any character of material is used for the superimposed layer. This is accomplished in the present embodiment of the invention by providing a main guiding instrumentality which is adapted to engage and preferably to embrace the edge of the superimposed layer and direct the same toward the stitching point, and a supplemental guiding instrumentality which is located nearer to the stitching point than the main guiding instrumentality and which is of a character to direct the thinner and more flexible material into the path of the needle.

In order that these guiding instrumentalities may be independently used, manually operable locking means are employed for retaining the same in guiding position and means also desirably are employed for withdrawing and withholding one or both of said guiding instrumentalities from guiding position when released.

A preferred embodiment of the invention is illustrated in the accompanying drawings as applied to a presser foot of a blind stitch sewing machine similar to that disclosed in my prior application No. 94,987 aforesaid.

In the drawings,

Figure 1 is a plan view of a pressed foot embodying a preferred form of my invention showing the main and supplemental guiding instrumentalities in guiding position;

Fig. 2 is a central longitudinal sectional view showing in elevation the inner wall of the minor toe portion and the ends of the guiding instrumentalities and the means for locking said instrumentalities in guiding position;

Fig. 3 is a transverse sectional view on lines 3—3 Fig. 1;

Fig. 4 is a plan view of the supplemental guiding instrumentality;

Fig. 5 is a plan view of the main guiding instrumentality.

The presser foot illustrated in the accom-

panying drawing which is particularly adapted to sewing machines for felling of the "Arbetter" type comprises a heel portion 1 having forwardly extending major and 5 minor toe portions 2, 3, and upwardly extending ears 4, 5 having suitable apertures 6, 7 for bolts or screws to secure the presser foot to the hook bracket or other supporting means upon the head of the sewing machine.

10 The rear central portion of the heel is provided with the usual recess 8 to receive the shank which extends from the bobbin case and prevents rotation of the latter within the rotary hook or looper. The major toe 15 portion is provided with a recess 9 which forms a needle throat within the area of which the needle enters the material being operated upon. The needle throat also serves to permit the base layer to be thrust 20 upwardly into the path of the oscillating needle by suitable bender mechanism in the well known manner.

A part, preferably about one half of the major toe portion, is reduced by milling or 25 otherwise to provide a needle guiding surface 10 for supporting the needle as it penetrates the material so that its point will not be deflected into engagement with the heel portion of the presser foot. The heel portion 30 also preferably is provided with a guiding surface 11 which serves to support the needle after it has passed through the material.

The inner edge of the toe portion also 35 desirably is provided with a rib 12 which engages the needle when the latter is penetrating the superimposed layer and prevents it from lateral deflection as it passes through the material, thus insuring the 40 proper amount of penetration into the thin superimposed layer.

The under surface of the minor toe portion has a curved cloth engaging face 13 which converges toward the stitching point 45 and extends a short distance beyond the needle throat where it forms with the wall 14 of a slot 15 in the front of the heel portion a guiding means which directs the edge of the superimposed layer beyond the stitching point. The curved surface 13 engages and bears upon the upper surface of the superimposed layer and by reason of its curvature and its convergence toward the stitching point operates to crowd the superimposed layer toward the major toe portion 55 and into the path of the needle.

In order properly to present the surface of the superimposed layer to the needle whether the superimposed layer is of thick 60 or thin material or of stiff or flexible material main and supplemental guiding instrumentalities are employed which engage the upper surface of the superimposed layer and preferably embrace the edge thereof 65 and so direct the edge of the layer as to

cause its under surface to pass at an angle across the path of the needle, the main guiding instrumentality being adapted to guide heavier and stiffer fabrics while the supplemental guiding instrumentality may be 70 operated to direct the thinner and more flexible material closely to the stitching point.

Means preferably are provided for independently locking these guiding instrumentalities in guiding position, said means being preferably adapted to release first 75 one and then the other of said guiding instrumentalities.

A preferred form of guiding means which 80 is illustrated herein comprises a main guiding instrumentality consisting of a plate 16 which is preferably of sheet metal having a curved conoidal end portion 17 to engage the upper surface and to embrace the 85 edge of the superimposed layer, said guide plate 16 having ears 18 which are pivotally mounted upon a shaft or stud 19 supported at one end in a recess 20 in the ear 5 and at its opposite end secured by a set screw 90 21 in a boss 22 extending upwardly from the forward end of the minor toe portion. The supplemental guiding instrumentality comprises a plate 23 having ears 24 which are pivoted upon a shaft or stud 95 25 which is anchored in the ears 18 of the main guiding member 16.

The curved conoidal guiding end portion 17 of the main guiding instrumentality serves to roll the edge of the superimposed layer into substantially conoidal form and direct it toward the stitching point. Where the superimposed layer is of relatively heavy goods it is properly presented in the path of the needle so that the needle will 105 enter the superimposed layer beneath its edge and emerge therefrom beneath or at the edge. Where the superimposed layer is composed of relatively thin and stiff material it is likely to roll upwardly out of the 110 path of the needle and require supplemental means for so directing it into the path of the needle that the formation of every stitch in it will be assured. The plate 23 therefore is employed to complete the guidance of 115 the superimposed layer in the manner aforesaid.

The plate 23 is provided with a rearward and downward extension 26, the lower surface or inner edge of which engages the 120 looped portion of the inturned edge of the superimposed layer as it emerges from the main guide 17 and serves to flatten it as it approaches the path of the needle.

The guiding portion 26 of said supplemental guiding instrumentality extends close to the path of the oscillating needle so that where thin material is operated upon, in which the loop of the superimposed layer might otherwise fail to pass across the 130

path of the needle, the superimposed guide will crush the loop down enough to present the under surface of the inturned portion of said layer unfailingly to the needle.

5 Any suitable means may be provided for locking the main and supplemental guiding instrumentalities in guiding position or for releasing them from such position and for holding them when released. In the preferred embodiment of the invention disclosed herein a helical spring 27 surrounding the stud 19 normally acts to withdraw or raise the main guiding instrumentality 16 from guiding position.

15 Likewise a helical spring 28 coiled upon the stud 25 operates normally to withdraw or raise the supplemental guiding instrumentality from guiding position. The means for locking said guiding instrumentalities in guiding position which is illustrated herein comprises a locking member 29 slidably mounted in a groove or channel 30 extending longitudinally of the minor toe portion and held therein by overlying plates 20 or guides 31, 32 which are secured to the presser foot respectively by the screws 21 and 33.

The locking member 29 has an upwardly projecting portion 34 which is provided with 30 detents 35 and 36 adapted respectively to overlie the block 24 of the supplemental guiding member and the plate 16 of the main guiding member. The detent 36 projects beyond the end of the detent 35 so that 35 when the locking member 29 is moved longitudinally the supplemental guiding member will be released and withdrawn from guiding position by its spring 28 while the main guiding member is retained in guiding position. Further movement however, of the locking member 29 will withdraw the detent 36 from its engagement with the member 16 and permit it to be removed from guiding position by the action of its spring 27.

40 45 The locking member 29 desirably is normally maintained in locking position by a helical spring 37 located in a recess 38 in the heel of the presser foot and which engages at its forward end a shoulder 39 upon 50 the member 29 and at its opposite end is seated against a screw plug 40 in said recess.

It will be understood that the present embodiment of the invention is illustrative and that various modifications in construction and arrangement of parts may be made 55 within the scope of the following claims.

Having thus described my invention what I claim as new and desire to secure by Letters Patent is:

60 1. A presser foot for sewing machines for felling a superimposed layer upon a base layer of material comprising toe portions adapted to engage respectively the base and superimposed layers, guiding means for the 65 superimposed layer including a plurality

of vertically movable guiding instrumentalities pivotally mounted upon the presser foot and operating successively to engage and direct said superimposed layer as the same approaches the stitching point and means 70 operable to remove one of said instrumentalities from guiding position.

2. A presser foot for sewing machines for felling a superimposed layer upon a base layer of material, comprising guiding means 75 for the superimposed layer including a plurality of guiding instrumentalities pivotally mounted upon the presser foot and operating successively to engage and direct said superimposed layer as the same approaches the stitching point, means including a locking device for holding said guiding instrumentalities in guiding position and operable to successively release and remove first one and then the other of said guiding 80 instrumentalities from guiding position.

3. A presser foot for sewing machines for felling a superimposed layer upon a base layer of material, comprising guiding means for the superimposed layer including a plurality of guiding instrumentalities operating successively to engage and direct the superimposed layer as the same approaches the stitching point and a device for locking 95 said instrumentalities in guiding position operable to release one of said guiding instrumentalities while retaining another in guiding position.

4. A presser foot for sewing machines for felling a superimposed layer upon a base 100 layer of material, comprising guiding means for the superimposed layer including a plurality of guiding instrumentalities pivotally mounted upon said presser foot operating successively to engage and direct said superimposed layer as the same approaches the stitching point and simultaneously operable means for locking both of said instrumentalities in guiding position but operable to release one of said instrumentalities while 105 retaining the other in guiding position, and independent means operating to withhold said instrumentalities respectively from guiding position when released.

5. A presser foot for sewing machines for 110 felling a superimposed layer upon a base layer of material, comprising main and supplementary guiding instrumentalities operating successively to engage and direct said superimposed layer as the same approaches the stitching point, means for locking 115 said guiding instrumentalities in guiding position, operable to release said supplementary guiding instrumentality while retaining the main guiding instrumentality in 120 guiding position and means independent of said locking means for retaining the released supplementary guiding instrumentality out of guiding position when thus released.

6. A presser foot for sewing machines for 125

65 superimposed layer including a plurality

1
felling a superimposed layer upon a base
layer of material, comprising main and supplemental
guiding instrumentalities positioned
successively to engage and direct said
superimposed layer as the same approaches
the stitching point, means for conjointly
locking said instrumentalities in guiding
position operable to release said supplemental
instrumentalities while retaining the main
10 guiding instrumentality in guiding position
and also operable to release said main guiding
instrumentality and means independent
of said locking means for withholding said
guiding instrumentalities from guiding po-
15 sition when released.

7. A presser foot for sewing machines for
felling a superimposed layer upon a base
layer of material, comprising pivotally
mounted guiding instrumentalities positioned
20 successively to engage and direct said
superimposed layer as the same approaches
the stitching point, independent resilient
means normally tending to withdraw said
guiding instrumentalities from guiding po-
25 sition and releasable means for locking said
guiding instrumentalities in guiding position.

8. A presser foot for sewing machines for
felling a superimposed layer upon a base
30 layer of material, comprising pivotally
mounted guiding instrumentalities positioned
successively to engage and direct said
superimposed layer as the same approaches
the stitching point, independent resilient
35 means normally tending to withdraw said
guiding instrumentalities from guiding po-
sition and releasable means for locking said
guiding instrumentalities in guiding position
operable independently successively to
40 release first one and then the other of said
guiding instrumentalities.

9. A presser foot for sewing machines for
felling a superimposed layer upon a base
45 layer of material, a pivotally mounted main
guiding instrumentality and a supplemental
pivotally mounted guiding instrumentality
overlying said main guiding instrumentality
and having guiding means extending beyond
50 said main guiding instrumentality toward
the stitching point, independent means nor-
mally tending to withdraw said guiding in-
strumentalities from guiding position and
means for independently locking said guid-
55 ing instrumentalities in guiding position
whereby one of said instrumentalities may
be released from guiding position while the
other is retained in guiding position.

10. A presser foot for sewing machines for
felling a superimposed layer upon a base
60 layer of material, a pivotally mounted main
guiding instrumentality and a supplemental
pivotally mounted guiding instrumentality
overlying said main guiding instrumentality
and having guiding means extending beyond
65 said main guiding instrumentality toward
the stitching point, independent means nor-
mally tending to withdraw said guiding in-
strumentalities from guiding position, a
member having detents adapted independ-
70 ently to engage said supplemental and main
guiding instrumentalities to lock the same
in guiding position and operable successively
to release first the supplemental guiding in-
strumentality and then the main guiding
75 instrumentality.

11. A presser foot for sewing machines for
felling a superimposed layer upon a base
80 layer of material, a pivotally mounted main
guiding instrumentality and a supplemental
pivotally mounted guiding instrumentality
overlying said main guiding instrumentality
and having guiding means extending beyond
85 said main guiding instrumentality toward the
stitching point, independent means normally
tending to withdraw said guiding instru-
mentalities from guiding position, a locking
member slidably mounted in said presser
90 foot having detents positioned to engage re-
spectively said supplemental and said main
guiding instrumentalities and operable to
release first one and then the other of said
guiding instrumentalities and resilient
95 means for normally holding said locking
member in locking position.

In testimony whereof, I have signed my
name to this specification.

THOMAS J. HAYES.
